UNITED STATES PATENT OFFICE.

LAURENCE V. BENÉT, OF PARIS, FRANCE.

SEMI-AUTOMATIC GUN.

SPECIFICATION forming part of Letters Patent No. 696,851, dated April 1, 1902.

Application filed June 20, 1901. Serial No. 65,322. (No model.)

To all whom it may concern:

Be it known that I, LAURENCE V. BENÉT, a citizen of the United States of America, residing at 21 Rue Royale, Paris, France, have 5 invented a certain new and useful Improvement in Semi-Automatic Guns; and I do hereby declare that the following is a full, clear, and exact specification of the same.

The present invention relates to that class 10 of guns known as "semi-automatic" guns, but more particularly to the construction of semi-automatic gun described in Letters Patent of the United States, No. 619,393, May 8, 1900.

15 The object of this invention is to render the dimensions of the closing-spring independent of the length of the recoil of the gun, to provide means for opening the breech, loading, and closing the breech during the recoil and 20 counter-recoil of the gun, and to increase the rate of fire of guns having a long recoil on their carriages.

In the previous construction the closing-spring which operates the closing of the breech 25 was attached at one end to a recoiling part of the mechanism and at the other to a non-recoiling part of the carriage or mounting. From this it followed that the extension of the spring, and consequently its total length, 30 was proportional to the length of the recoil of the gun. In the short-recoil mountings considered in the previous patent this feature was of little moment; but when it is desirable to give to the gun a very long recoil, 35 as in the case of field-artillery, the spring becomes long and difficult of manufacture and is subjected to undue and destructive strain. In the present improvement the mechanism is so arranged that both ends of the closing- 40 spring are attached to recoiling elements, from which it follows that the length of the spring and the strain to which it is subjected are independent of the length of the recoil of the gun and that its action is limited to the 45 simple function of closing the breech. In the case of a short-recoil gun, as illustrated in the previous patent, the action of the semi-automatic mechanism was such that the breech of the gun remained closed during the recoil 50 and only began to open when the counter-recoil was partially accomplished. This se-

quence of movements was necessary from the fact that it is dangerous to unlock or open the breech before the pressure in the bore of the gun has been reduced to essentially that of 55 the atmosphere. In a short-recoil gun this condition does not exist until the gun has so far recoiled that the remaining recoil to be accomplished is not sufficient to operate the breech-opening mechanism. In a long- 60 recoil gun, however, the pressure in the bore of the gun is reduced to that of the atmosphere long before the recoil is completed, and therefore there is no danger in opening the breech during the latter part of the recoil of 65 the gun. By so arranging the mechanism a very great gain in the rapidity of fire is obtained, for the gun may be readily reloaded during the counter-recoil, and therefore arrive in battery in readiness for firing. Thus 70 the entire time required to open the breech, extract and eject the spent-cartridge case, to reload the gun and close the breech is saved, all of these operations being performed during the time required for the recoil and the 75 counter-recoil. The length of the recoil of the gun, and consequently the time required, is determined by certain elements dependent upon the nature of the service and cannot therefore be reduced. Hence by this invention 80 the maximum possible rate of fire is obtained under these special conditions. This result is accomplished by a mechanism which is so devised that as the recoil is completed the breech will be opened and that as the gun is 85 loaded during the return to battery the breech will be closed during this movement.

In the accompanying drawings, Figure 1 is a side elevation of gun and mounting, showing the gun as loaded with the breech closed 90 and ready for firing. Fig. 2 is one-half of the corresponding view in plan. Fig. 3 is a cross-section on the line A A of Fig. 1. Fig. 4 is an elevation similar to Fig. 1, but showing the gun at a certain stage of its recoil. Fig. 5 is 95 an elevation similar to Fig. 1, but showing the gun at a certain further stage of its recoil. Fig. 6 is an elevation similar to Fig. 1, but showing the gun at a certain further stage as it has completed its recoil and is about to return to battery. Figs. 7 and 8 are details relating to the extractor.

Before describing the construction of the semi-automatic gun it is necessary to recall the object of the extractor and to remember its function, which consists simply, both in the present construction and in the construction set forth in the prior patent, in locking the breech-block in its open position and in unlocking the same while the gun is being reloaded in order that the mechanism may then act to close the breech again. The arrangement of this extractor 3 being known and its functions being the same, there is no need to enter into a description of its construction, except that it moves in a groove 4 and has a stud 6, which rests on a horizontal abutment 2 at the top of the inclined portion 7 of the groove 1, formed in the breech-block, and that it has at one end the usual claw 5, while at the other end it has a shoulder 9, Figs. 7 and 8, which acts to retain the extractor in the position shown in Fig. 8 until it is caused to be unlocked by the act of introducing a cartridge into the gun, as clearly stated in the prior patent.

On the hub 15 of the crank-handle 16 is formed a pair of lugs 17, between which is pivoted on a pin 18 the lug 19 of a rod 20. The crank-handle 16 has an eye 21, to which is engaged one end of a stout spiral spring 22, the other end of which is connected to an eye 25, fastened to a recoiling portion of the system—say to the gun itself. The rod 20 passes in a guide 23, which is fastened to a non-recoiling portion of the system—say to the cradle 27, Fig. 3, of the mounting—and is held continually depressed by a spring 24. Toward the middle its top surface is formed into a hump 26. Its under surface is formed into an abutment 28, and its free end 29 acts as a support, as hereinafter explained. The pivoted end of the rod 20 is provided with a tang 30, and the hub 15 of the crank-handle 16 is provided with a cam 31, co-operating therewith, as hereinafter explained. On the guide 23 is formed an abutment 32, coacting, as hereinafter stated, with the abutment 28 on the rod 20.

The action of the mechanism is as follows: If the gun be fired, the parts having the position shown in Fig. 1, the gun will recoil until it reaches a first stage, which is that shown in Fig. 4, wherein the rod 20, having been carried along, will strike with its abutment 28 against the abutment 32 on the stationary guide 23. From that moment on the rod will be arrested, but the gun will continue to recoil, whereby the breech-block will be operated on and the breech opened, as in the prior patent, whereupon the gun will reach a second stage, which is that shown in Fig. 5. As the parts reach the position shown in Fig. 5 the hump 26 is within the guide 23, its upper face in close contact with the spring 24, against which it presses. Any further upward movement of the hump 26 being prevented, it follows that as the breech-block moves down the

weight thereof will be received by the rod 20, thus relieving the breech-bolt 33 from injury due to any possible severe shock. With the parts in the position illustrated in Fig. 5 the cam 31 depresses the tang 30, and thus causes the rod 20 to be tilted, thereby freeing its abutment 28 from the stationary abutment 32. The recoil will still continue to take place until the third stage is reached, which is that shown in Fig. 6, wherein the recoil is completely effected, the breech open, and the spring 22 under tension. The gun then returns to battery, and while so doing the loading operation may be performed in the usual manner. The act of inserting a cartridge unlocks the breech-block, and the spring 22 then operates to raise the breech-block and close the breech, the latter being closed and the gun ready for firing by the time the return to battery is completed.

The gun is returned to battery by means of the usual spring contained in the recoil-checking cylinder.

It will be observed that the spring 22 is not subjected to any strain dependent upon the amount of recoil of the gun, but that its extension and contraction are invariably the same. The only condition which it is required to satisfy is that it shall be capable of storing up sufficient energy to raise the breech-block and close the breech.

It goes without saying that if the spring 22 be removed, or if the rod 20 be disengaged from the lugs of the crank-handle 16, the opening and closing of the breech may be operated by hand, as in the case of an ordinary quick-firing gun. It is also obvious that the cradle and other details of the mounting illustrated in the accompanying drawings have only been shown as an example and that they may be replaced by any other system or form of gun-carriage.

While this invention is shown as applied to the mechanism of the well-known Hotchkiss quick-firing guns, it is evident that it may be applied in whole or in part, with or without slight or considerable modifications, to the mechanism of quick-firing guns of any system, whatever. The present invention is therefore not limited to this particular application.

I claim—

1. In a long-recoil semi-automatic gun, the combination with the gun-body and breech mechanism, of a spring under tension carried by the gun-body, and connected to said gun-body and said breech mechanism, and a lever and actuating-rod operated at any predetermined point of the recoil for actuating said breech mechanism against the action of said spring, substantially as described.

2. In a long-recoil semi-automatic gun, the combination with the gun-body and breech mechanism, of a spring under tension carried by the gun-body and connected to said gun-body and said breech mechanism, and an ac-

- tuating-rod carried by the gun and engaging the gun-mount at any predetermined point of the recoil of the gun for operating said breech mechanism against the action of said spring, substantially as described. 5
3. In a long-recoil semi-automatic gun, the combination with the gun-body and breech mechanism, of a spring under tension carried by the gun-body and connected to said gun-body and said breech mechanism, a rod carried by the gun and operated by engagement with the gun-mount at any predetermined point of the recoil of the gun for actuating said breech mechanism against the action of said spring, and independent means for holding the breech mechanism in the open position and for releasing the same, substantially as described. 10
4. In a long-recoil semi-automatic gun, the combination with the gun-mount, the gun-body and breech mechanism, of a spring under tension carried by the gun-body, and connected to said gun-body and said breech mechanism, an operating-lever, and an actuating-rod engaging a stop on the gun-mount at any predetermined point of the recoil, for actuating said breech mechanism against the action of said spring, substantially as described. 15
5. In a long-recoil semi-automatic gun, the combination with the gun-mount, the gun-body and breech mechanism, of a spring under tension carried by the gun-body, and connected to said gun-body and said breech mechanism, an operating-lever, and an actuating-rod engaging a stop on the gun-mount at any predetermined point of the recoil, for actuating said breech mechanism against the action of said spring, and independent means 20 for holding said breech mechanism in the open position and for releasing the same to be automatically closed by said spring, substantially as described. 25
6. In a long-recoil semi-automatic gun, the combination with the gun-mount, the gun-body and breech mechanism, of a spring under tension carried by the gun-body, and connected to said gun-body and said breech mechanism, an operating-lever and an actuating-rod engaging a stop on the gun-mount at any predetermined point of the recoil, for actuating said breech mechanism against the action of said spring, and an extractor for holding said breech mechanism in the open 30 position and for releasing the same to be automatically closed by said spring, substantially as described. 35
7. In a long-recoil semi-automatic gun, the combination with the gun-body and breech mechanism, of a spring under tension carried by the gun-body and connected to said gun-body and said breech mechanism, an actuating-rod carried by the gun and engaging the gun-mount at any predetermined point of the recoil of the gun for operating said breech mechanism against the action of said 40
- spring, and an extractor locking the breech mechanism in the open position and automatically releasing same on the insertion of a cartridge, substantially as described. 70
8. In a long-recoil semi-automatic gun, the combination with the gun-body and breech mechanism, of a spring under tension carried by the gun-body and connected to said gun-body and said breech mechanism, a rod carried by the gun and operated by engagement with the gun-mount at any predetermined point of the recoil of the gun for actuating said breech mechanism against the action of said spring and then releasing said mechanism, and an extractor automatically holding the breech mechanism in the open position and automatically releasing the same, on the insertion of a cartridge-case, substantially as 75 described. 80
9. In a long-recoil semi-automatic gun, the combination with the gun-body and breech-block, and a lever for operating said breech-block, having a downwardly-projecting arm, of a spring under tension carried by the gun-body and connected to said gun-body and to said lever and a rod pivoted to the lower arm of said lever and operated by engagement with the gun-mount at any predetermined point of the recoil of the gun for rocking said lever against the action of said spring and thus moving said breech-block to the open position, substantially as described. 90
10. In a long-recoil semi-automatic gun, the combination with the gun-body and breech-block, and a lever for operating said breech-block, having a downwardly-projecting arm, of a spring under tension carried by the gun-body and connected to said gun-body and to said lever, a rod pivoted to the lower arm of said lever and operated by engagement with the gun-mount at any predetermined point of the recoil of the gun, for rocking said lever against the action of said spring, and thus moving said breech-block to the open position, and independent means for holding the breech-block in the open position and for releasing same when desired, substantially as 100 described. 105
11. In a long-recoil semi-automatic gun, the combination with the gun-body and breech-block, and a lever for operating said breech-block, having a downwardly-projecting arm, of a spring under tension carried by the gun-body and connected to said gun-body and to said lever, a rod pivoted to the lower arm of said lever and operated by engagement with the gun-mount at any predetermined point of the recoil of the gun, for rocking said lever against the action of said spring and thus 110 moving said breech-block to the open position, and an extractor holding the breech-block in the open position and automatically releasing the same on the insertion of a cartridge-case, substantially as described. 115
12. In a long-recoil semi-automatic gun, the combination with the gun-mount, the gun- 120

body and breech mechanism, of a spring under tension carried by the gun-body, and connected to said gun-body and said breech mechanism, an operating-lever, an actuating-rod engaging a stop on the gun-mount at any predetermined point of the recoil, for actuating said breech mechanism against the action of said spring, and means for throwing said rod out of engagement with the gun-mount when the breech is completely open, substantially as described.

13. In a long-recoil semi-automatic gun, the combination with the gun-mount, the gun-body and breech mechanism, of a spring under tension carried by the gun-body, and connected to said gun-body and said breech mechanism, an operating-lever, an actuating-rod engaging a stop on the gun-mount at any predetermined point of the recoil, for actuating said breech mechanism against the action of said spring, means operated by said lever for throwing said rod out of engagement with the gun-mount when the breech is completely open, and independent means for holding said breech mechanism in the open position and for releasing the same to be automatically closed by said spring, substantially as described.

14. In a long-recoil semi-automatic gun, the combination with the gun-mount, the gun-body and breech mechanism, of a spring under tension carried by the gun-body, and connected to said gun-body and said breech mechanism, an operating-lever, an actuating-rod engaging a stop on the gun-mount at any predetermined point of the recoil, for actuating said breech mechanism against the action of said spring, means operated by said lever for throwing said rod out of engagement with the gun-mount when the breech is completely open, and an extractor for holding said breech mechanism in the open position and for releasing the same to be automatically closed by said spring, substantially as described.

15. In a long-recoil semi-automatic gun, the combination with the gun-body and breech mechanism, of a spring under tension carried by the gun-body and connected to said gun-body and said breech mechanism, an actuating-rod carried by the gun and engaging the gun-mount at any predetermined point of the recoil of the gun for operating said breech mechanism against the action of said spring, means operated by said lever for throwing said rod out of engagement with the gun-mount when the breech is completely open, and an extractor locking the breech mechanism in the open position and automatically releasing same on the insertion of a cartridge, substantially as described.

16. In a long-recoil semi-automatic gun, the combination with the gun-body and breech-

block, and a lever for operating said breech-block, having a downwardly-projecting arm, of a spring under tension carried by the gun-body and connected to said gun-body and to said lever, a rod pivoted to the lower arm of said lever and operated by engagement with the gun-mount at any predetermined point of the recoil of the gun for rocking said lever against the action of said spring, and bearing-faces on said lower arm and on said rod to automatically trip the latter clear of engagement with said gun-mount when the breech is completely open.

17. In a long-recoil semi-automatic gun, the combination with the gun-body and breech-block, and a lever for operating said breech-block, having a downwardly-projecting arm, of a spring under tension carried by the gun-body and connected to said gun-body and to said lever, a rod pivoted to the lower arm of said lever and operated by engagement with the gun-mount at any predetermined point of the recoil of the gun, for rocking said lever against the action of said spring, and thus moving said breech-block to the open position, bearing-faces on said lower arm and on said rod to automatically trip the latter clear of engagement with said gun-mount when the breech is completely open, and independent means for holding the breech-block in the open position and for releasing same when desired, substantially as described.

18. In a long-recoil semi-automatic gun, the combination with the gun-body and breech-block, and a lever for operating said breech-block, having a downwardly-projecting arm, of a spring under tension carried by the gun-body and connected to said gun-body and to said lever, a rod pivoted to the lower arm of said lever and operated by engagement with the gun-mount at any predetermined point of the recoil of the gun, for rocking said lever against the action of said spring and thus moving said breech-block to the open position, bearing-faces on said lower arm and on said rod to automatically trip the latter clear of engagement with said gun-mount when the breech is completely open, and an extractor holding the breech-block in the open position and automatically releasing the same on the insertion of a cartridge-case, substantially as described.

In witness whereof I have hereunto set my hand, this 8th day of June, 1901, in the presence of subscribing witnesses.
